Original application November 27, 1929, Serial
No. 410,020. Divided and this application
October 6, 1933, Serial No. 692,373. In Ger-
many November 30, 1928

9 Claims. (Cl. 62—119.5)

This invention relates to continuous absorption refrigerating apparatus, and more particularly to the boiler or generator and the absorber and the manner in which these devices cooperate with the other parts of the refrigerating system.

This application is a divisional case of U. S. application Serial No. 410,020 filed November 27, 1929, issued as Patent No. 1,951,336 on March 20, 1934 for process and apparatus for heat exchange between two currents of gas. An application corresponding to application Serial No. 410,020 was filed in Germany November 30, 1928.

In continuous absorption refrigerating systems operating with ammonia or other refrigerant of like nature where the vapor pressure of the refrigerant is considerably higher in the boiler than in the other parts of the system, considerable difficulty has been experienced in successfully operating the unit on account of corrosion. The metal of which the apparatus is constructed is apt to decompose in those parts of the system where it is subjected to the fluids at high temperature and vapor pressure.

It is an object of the present invention to provide a boiler system of such a nature that it may operate at a comparatively low temperature. Thus corrosion is largely prevented.

It is a further object of the invention to provide a novel combination of boilers and absorbers which will permit the refrigerating apparatus to operate under conditions tending to reduce the amount of corrosion.

It is a further object of the invention to provide a novel refrigerating apparatus employing an inert gas or other auxiliary pressure equalizing medium, in which the inert gas is circulated over more than a single path so as to improve the operation of the unit.

It is a further object to provide a refrigerating apparatus so arranged as to enable the absorber to operate under the favorable condition of a low solution concentration range while the boiler operates under the favorable condition of a high concentration range.

Other objects and advantages reside in novel features of the arrangement and construction of parts and will be apparent from a consideration of the following description taken in connection with the accompanying drawing in which:

The single figure of the drawing is a diagrammatic representation of a continuous absorption refrigerating system constructed in accordance with the principles of the present invention.

The continuous absorption refrigerating system illustrated in the drawing consists of a main

boiler 41, of usual construction, a gas separation chamber 43, a second or auxiliary boiler 50, a condenser 45, an evaporator 48, an absorber 52, and a second absorber 58, these parts being connected by various conduits to form the complete system.

A pipe 42 of small diameter constitutes a gas pipe of the usual construction for conveying refrigerant gas and absorption liquid from the main boiler 41 into the gas separation chamber 43. The refrigerant gas is conveyed from the gas separating chamber 43 to the condenser 45 by means of a gas conduit 44. In the condenser 45 the refrigerant gas is liquefied and conveyed by means of a U-pipe 46 and a small chamber 47 into the evaporator 48.

The evaporator 48 may be of the usual construction consisting merely of a cylindrical vessel provided with a number of baffle plates therein.

The auxiliary boiler 50 consists merely of a closed vessel provided with baffles and with some means for heating it. It is connected to the gas separating chamber 43 by a U-shaped conduit 49. The conduit 49 serves to convey absorption liquid from the bottom of the gas separation chamber 43 to the top of the auxiliary boiler 50.

The boiler 41, the gas separating chamber 43 and the auxiliary boiler together with the connecting conduits, constitute what may be called a two-stage or compound boiler, the operation of which will be described later.

A U-shaped conduit 51 conveys absorption liquid from the bottom of the auxiliary boiler 50 to the top of the main absorber 52.

The absorber 52 may be of the usual type consisting merely of a cylindrical vessel provided with a number of baffle plates.

Inert gas is circulated between the evaporator 48 and the main absorber 52 by means of the gas conduits 53 and 54, these gas conduits being in heat exchange relation over a portion of their length as indicated at 55. For draining liquids which may collect in the bottom of the evaporator back to the absorption liquid circulation system, a small U-shaped conduit 56 connects the bottom of the evaporator to the horizontal portion of the gas conduit 54.

The bottom of the main absorber 52 is connected to the top of the auxiliary absorber 58 by means of a conduit 57. This conduit not only serves to drain absorption liquid from the main absorber 52 to the auxiliary absorber 58 but it is also of sufficient size to permit gases to flow from one absorber to the other. The conduit thus acts as an equalizer or means for maintaining the

total pressure in the absorber 58 the same as that in the absorber 52.

The auxiliary absorber 58 may be similar to the main absorber 52 and consist merely of a cylindrical vessel provided with a number of baffle plates.

For conveying absorption liquid from the auxiliary absorber 58 back to the main boiler 41, the U-shaped conduit 59 is provided, this conduit passing in heat exchange relation with portions of the liquid conduits 49 and 51.

Inert gas is also circulated between the auxiliary boiler 50 and the auxiliary absorber 58, this being accomplished by means of the gas conduits 60 and 61, the upper portions of which are in heat exchange relation.

To promote this circulation a jet 62 may be provided in accordance with known practices, this jet being supplied with refrigerant gas coming from the gas separation chamber 43.

Assuming that the system just described is charged with ammonia as refrigerant, water as absorption liquid and hydrogen as inert gas, and that heat is applied to the boilers 41 and 50, four separate cycles of circulation will be set up, one for the refrigerant, one for the absorption liquid and two for the inert gas.

The refrigerant will pass over a cycle (neglecting that part passing through the jet 62) as follows:

Starting with the boiler 41 the refrigerant will pass upwardly through the gas lift pump conduit 42, the gas separation chamber 43, the gas conduit 44, a portion of which may act as a rectifier, condenser 45, the supply conduit 46, vessel 47, the evaporator 48, in which the refrigerant will evaporate and be conveyed by the inert gas through the conduit 54 into the first absorber 52, and thence through the conduit 57 into the second absorber 58. In the absorbers 52 and 58 the refrigerant will be absorbed and conveyed back into the boiler 41 through the conduit 59.

The absorption liquid will pass through a cycle starting with the boiler 41 upwardly through the gas lift pump conduits 42, the gas separation chamber 43 from which it will flow through the conduit 49 into the auxiliary boiler 50 and from there into the top of the absorber 52 through the conduit 51. After trickling down over the baffle plates in the main absorber 52 the liquid will pass through the conduit 57 into the auxiliary absorber 58. After trickling downwardly over the baffle plates therein it will be conveyed back to the boiler 41 through the conduit 59.

One of the inert gas circuits will be between the evaporator 48 and the main absorber 52, the gas leaving the top of the evaporator and flowing to the bottom of the absorber 52 through the conduit 54 and after passing upwardly through the absorber 52 flowing back to the lower portion of the evaporator through the gas conduit 53.

Another inert gas circuit is, as mentioned above, between the auxiliary boiler 50 and the auxiliary absorber 58. The gas in this circuit is impelled by the refrigerant gas passing through the jet 62. The inert gas leaves the top of the auxiliary boiler 50 and flows into the bottom of the auxiliary absorber 58 through the conduit 61. It then returns to the lower portion of the auxiliary boiler 50, after passing upwardly over the plates in the auxiliary absorber 58, through the gas conduit 60.

As stated above, heat is applied to the main boiler 41. Heat is also applied to the auxiliary boiler 50 and it is in this respect that the system

differs from the usual ammonia absorption system using an inert gas.

In the system illustrated the refrigerant vapor expelled in the main boiler 41 is condensed in the condenser 45, evaporated in the evaporator 48 and conveyed to the absorber 52 by an inert gas circuit just the same as in the known types of condensing ammonia absorption systems. The weak solution leaving the main boiler 41, however, is conducted to the inert gas filled boiler 50, in which the solution concentration is further decreased by vaporizing the refrigerant into the inert gas stream at a temperature which may be either the same as that of the main boiler 41 or either higher or lower than the temperature of the main boiler, the boiler 50 operating at a lower refrigerant vapor pressure than the boiler 41 due to the presence of inert gas in the boiler 50. The refrigerant vapor expelled in the auxiliary boiler 50 is not put to any useful work in so far as refrigeration is concerned, but is absorbed back into the solution in the auxiliary absorber 58 following the main absorption process in the absorber 52. The advantage gained by the use of the compound boiler and absorber results from the fact that because of the employment of the auxiliary boiler 50, the absorption liquid supplied to the main absorber 52 through the conduit 51 is considerably weaker than would otherwise be the case.

It will thus be seen that means for supplying a refrigerant at a low concentration to the main absorber is provided without the necessity of heating the absorption liquid in the boiler system to a high temperature. Because of the fact that corrosion and decomposition take place in systems of this nature much more rapidly at high temperatures, any feature which tends to reduce the boiler temperature without adversely affecting the operation of the unit as a whole, is highly desirable. Thus one advantage of the present system becomes apparent. Another advantage results from the fact that the main absorber 52 may operate at a lower temperature than usual and thus facilitates absorption of the refrigerant from the evaporator.

In order to illustrate the advantages of the present invention an example is given of its application to an air cooled system using ammonia, water and hydrogen as fluids and operating under somewhat standard test conditions.

Assuming that it is desirable to operate the main absorber 52 at a temperature around 120 degrees F. so that it may operate satisfactorily in a 100 degrees F. room, the present invention makes it possible to supply the absorption liquid to the absorber 52 at a concentration of about 10%. This would permit an absorption solution concentration range from 10% to 25% in the absorber 52 and would give excellent results in so far as absorption is concerned. However, if this range were employed in the usual continuous inert gas type of system using ammonia as refrigerant, a boiler temperature of approximately 380 degrees would be required, assuming that the unit is operating at a total pressure of around 350 pounds per square inch absolute pressure.

By the application of the principles of the present invention, on the other hand, the temperature of the boiler 41 may be reduced to a temperature of about 320 degrees F. To accomplish this, the boiler 41 would not operate over the concentration range indicated above, but

would operate over a concentration range of, say from 35% down to 22 5% concentration.

The auxiliary boiler 50 and the auxiliary absorber 58 make this difference in concentration 5 ranges possible, the auxiliary boiler lowering the concentration of the solution passing to the main absorber from 22.5% to 10% and the auxiliary absorber 58 raising the concentration of the solution passing through it from 25% to 35%.

10 At the total pressure noted above, the auxiliary boiler temperature need not be high to accomplish this further reduction in the solution concentration, a temperature around 260° F. being high enough due to the fact that the refrigerant vapor pressure in the auxiliary boiler has been 15 reduced, due to the pressure of the inert gas therein, down to as low as 80 pounds per square inch, absolute.

20 No difficulty is experienced in absorbing the refrigerant expelled in the auxiliary boiler, back into the solution in the auxiliary absorber, because the latter may operate at a temperature higher than the main absorber without adversely affecting the operation of the unit as a whole.

25 Satisfactory operation may be obtained in the example given with the main absorber operating at a temperature around 120° F., as noted above, and the auxiliary absorber operating at a temperature in the neighborhood of 130° F. The refrigerant vapor pressure in the auxiliary absorber is, of course, correspondingly higher in the auxiliary absorber than in the main absorber.

30 Thus in the example illustrated the boiler temperature might be reduced 60 degrees F., that is, from 380 degrees to 320 degrees, by the application of the present invention to a known type of refrigerating apparatus operating under normal conditions.

35 It is apparent that certain features of the invention are applicable to various types of refrigerating apparatus such as those in which a resorber is used instead of the condenser illustrated and in many other types of units. Accordingly it is understood that various changes may 40 be made in the arrangement without departing from the spirit of the invention or the scope of the annexed claims.

I claim:

1. In a continuous absorption refrigerating system, the combination of a main boiler, a main absorber, an auxiliary boiler and an auxiliary absorber, means for conveying absorption liquid from the main boiler to the auxiliary boiler, from the auxiliary boiler to the main absorber, from the main absorber to the auxiliary absorber and from the auxiliary absorber back to the main boiler, means for expelling refrigerant from the solution in the main boiler, for causing the same to produce cooling effect and for conveying the same into the main absorber, means for expelling refrigerant from the solution in the auxiliary boiler to lower the concentration of the solution as it passes from the main boiler to the main absorber and means utilizing inert gas for conveying the refrigerant expelled in the auxiliary boiler to the auxiliary absorber.

2. In a continuous absorption refrigerating system, the combination with an absorber, a boiler and means for circulating absorption liquid therebetween, of means for lowering the concentration of the absorption liquid as it passes from the boiler to the absorber and for raising the concentration of the absorption liquid as it passes from the absorber back to the boiler, said means comprising an auxiliary boiler, an auxiliary ab-

sorber and means for circulating inert gas between the auxiliary boiler and the auxiliary absorber to transfer refrigerant from the auxiliary boiler to the auxiliary absorber.

3. In a continuous absorption refrigerating system, the combination with an absorber, a boiler and means for circulating absorption liquid therebetween, of means for lowering the concentration of the absorption liquid as it passes from the boiler to the absorber and for raising the concentration of the absorption liquid as it passes from the absorber back to the boiler, said means including an auxiliary boiler, an auxiliary absorber and means including conduits adapted to circulate inert gas between the auxiliary boiler 10 and the auxiliary absorber for expelling refrigerant from solution in the auxiliary boiler and for causing the same to be absorbed in the auxiliary absorber at a concentration range higher than that prevailing in the main absorber and lower 15 than that prevailing in the main boiler during operation of the system.

4. In a continuous absorption refrigerating system, the combination with an absorber, a boiler and means for circulating absorption liquid 20 therebetween, of means for lowering the concentration of the absorption liquid as it passes from the boiler to the absorber and means for raising the concentration of the absorption liquid as it passes from the absorber back to the 25 boiler, said means comprising an auxiliary boiler, an auxiliary absorber and means for circulating an inert gas in a cycle between the auxiliary boiler and the auxiliary absorber to transfer refrigerant 30 from the solution in the auxiliary boiler to solution in the auxiliary absorber.

5. In a continuous absorption refrigerating system, a compound boiler arrangement consisting of a main boiler, an auxiliary boiler, means for causing absorption liquid laden with refrigerant to flow through the boiler arrangement, passing from the main boiler to the auxiliary boiler, means for heating the main boiler to expel refrigerant from the absorption liquid flowing therethrough and thereby lower the concentration 45 of the solution flowing to the auxiliary boiler, means for heating the auxiliary boiler to further lower the concentration of the solution and means utilizing inert gas for causing the auxiliary boiler 50 to operate with the refrigerant vapor pressure therein lower than that prevailing in the main boiler.

6. In a continuous absorption refrigerating system, a compound boiler arrangement consisting of a main boiler, an auxiliary boiler, means for causing absorption liquid laden with refrigerant to flow through the boiler arrangement, passing from the main boiler to the auxiliary boiler, means for heating the main boiler to expel refrigerant from the absorption liquid flowing therethrough and thereby lower the concentration of the solution flowing to the auxiliary boiler, means for heating the auxiliary boiler to further lower the concentration of the solution and means for causing the auxiliary boiler to operate with the 60 refrigerant vapor pressure therein lower than that prevailing in the main boiler, said last mentioned means including conduits for circulating an inert gas through the auxiliary boiler.

7. A continuous absorption refrigerating system 70 comprising a main boiler, an auxiliary boiler, a condenser, an evaporator, a main absorber, an auxiliary absorber, means for circulating absorption liquid through the boilers and the absorbers, means for circulating an inert gas between the 75

main absorber and the evaporator and means for circulating an inert gas through the auxiliary boiler and the auxiliary absorber.

8. In the method of refrigerating by a continuous absorption refrigerating process having the steps of expelling a refrigerant from a solution, causing the expelled refrigerant to change to a more dense fluid phase, lowering the vapor pressure of the condensed refrigerant to cause the same to evaporate to produce a cooling effect, and absorbing the evaporated refrigerant back into the solution, the further steps of subjecting the weakened solution from which the refrigerant has been expelled to heat in the presence of an inert gas and at a refrigerant vapor pressure lower than that prevailing during the first mentioned expulsion to further weaken the same and causing the refrigerant expelled by the last mentioned step to be again absorbed by the solution.

9. In the method of refrigerating by a continuous absorption refrigerating process having the steps of expelling a refrigerant from a solution, causing the expelled refrigerant to change to a more dense fluid phase, lowering the vapor pressure of the condensed refrigerant by bringing it into the presence of an inert gas, thereby causing the refrigerant to evaporate and produce a cooling effect and absorbing the evaporated refrigerant back into the absorption solution, the further steps of bringing the weakened solution resulting from the first named expulsion into the presence of an inert gas and heating the same to further weaken the solution and conveying the mixture of inert gas and refrigerant resulting from the last named step into the presence of the absorption solution to cause the refrigerant to be again absorbed.

EDMUND ALTENKIRCH.
